(No Model.)

J. DOUGHTY.
BICYCLE BELL.

No. 597,106.

Patented Jan. 11, 1898.

INVENTOR.

UNITED STATES PATENT OFFICE.

JOHN DOUGHTY, OF PHILADELPHIA, PENNSYLVANIA.

BICYCLE-BELL.

SPECIFICATION forming part of Letters Patent No. 597,106, dated January 11, 1898.

Application filed April 1, 1897. Serial No. 630,285. (No model.)

To all whom it may concern:

Be it known that I, JOHN DOUGHTY, a citizen of the United States, residing in the city and county of Philadelphia, State of Pennsylvania, have invented a new and useful Improvement in Alarms for Bicycles, which improvement is fully set forth in the following specification and accompanying drawings.

My invention consists of an improved construction of bicycle-alarm which can be cheaply manufactured and readily and expeditiously applied to existing bicycles, the sounding of the alarm being caused by the rotation of the bicycle-wheel at the will of the rider.

It further consists of novel details of construction, all as will be hereinafter set forth, and fully pointed out in the claims.

Figure 1 represents a perspective view of a bicycle-alarm embodying my invention and a portion of a bicycle to which the same is applicable. Fig. 2 represents a section on line xx , Fig. 1. Fig. 3 represents a perspective view of a portion of the bell and the clamping device for securing the same to a bicycle-fork. Fig. 4 represents a front elevation of a portion of a bicycle-fork, showing the bell or alarm clamped in position thereon.

Similar letters of reference indicate corresponding parts in the figures.

Referring to the drawings, A designates a fork of a bicycle, and B, C, and D the handle-bar, wheel, and spokes, of the latter, the above parts being of the usual construction and requiring no further description.

E designates a bell adapted to be secured to a member of the bicycle-fork, the bell being illustrated in the present instance as secured to the left-hand member of the front fork.

F designates a portion of the clamping device employed, the same consisting of a strip having the tongue G at or near the extremity thereof, said tongue being provided with the neck G' and head H and adapted to enter an opening J in the plate J', said strip being held in position by means of a screw or other fastening device K when the parts are assembled.

L designates a spring or resilient vibratile member which has one end secured to the strip F in any suitable manner, while its opposite or free end is tipped with rubber or

other similar material M and is provided with the hammer N, which is adapted to vibrate against the bell E when desired, as will be explained.

P designates an angular or other shaped lever having the member Q, which is pivotally attached to the strip F at the point S or to some other fixed point, while the other portion R of said lever has an end of a string, cord, or other connection attached thereto, the other end thereof being secured to a suitable operating device on the handle-bar B or other point adjacent the rider.

The operation is as follows: The parts appear normally as seen in full lines in Fig. 2, in which position the extremity M of the member L is out of the path of the revolving spokes. When it is desired to sound the bell, the rider exerts a pull on the string T and the lever P, thereby bringing the member L into the position in the path of the rotating spokes D, whereby a series of impulses will be given to the hammer N, and the latter will contact with the bell E, thereby sounding the alarm. The strip F of the clamping device is placed in position by turning the head F from the position seen in Fig. 3, so that the tongue G can be readily inserted in the slot J and then turned into the position seen in Figs. 2 and 4, as is evident. When the strain on the connection T is relaxed, the member L assumes the position seen in full lines again.

The clip or clamping device may be provided with a pin (shown in dotted lines, Fig. 1) as means for carrying the lamp of the bicycle.

Having thus described my invention, what I claim as new, and desire to secure by Letters Patent, is—

1. A bicycle-alarm consisting of a bell, means for securing it to the frame of a bicycle, a resilient member connected at one end with said securing means and provided with a hammer adapted to strike said bell, a lever bearing against said resilient member, and a connection for operating said lever.

2. A bicycle-alarm consisting of a bell, a plate connected therewith, a strip detachably connected with said plate for supporting said bell, a resilient member connected at one end with said strip and having at its free end a tip of yielding material, a bell-hammer at

tached to said member, a lever pivoted to said strip and bearing against said member, and a connection from said lever adapted to be operated by the rider.

5 3. A bicycle-alarm consisting of a bell E, a plate J' on which said bell is supported, an opening J in said plate, a strip F having a tongue G and adapted to enter said opening, a resilient member L attached to said strip F

and provided with a tip M of yielding material, a hammer N attached to said member L, an angular-shaped lever P suitably supported, and a connection from said lever adapted to be operated by the rider.

JOHN DOUGHTY.

Witnesses:

JOHN A. WIEDERSHEIM,

W.M. C. WIEDERSHEIM.
